INVENTOR:

John C. Eckert.

United States Patent Office.

JOHN C. ECKERT, OF DAYTON, OHIO.

Letters Patent No. 83,142, dated October 20, 1868.

RAILROAD-CAR HEATER

The Schedule referred to in these Letters Patent and making part of the same.

Be it known that I, JOHN C. ECKERT, of Dayton, in the county of Montgomery, and State of Ohio, have invented a new and useful Improvement in Safety-Stoves for Heating Railroad-Cars with coal or wood; and I do hereby declare that the following is a full, clear, and exact description of the construction and operation of the same, reference being had to the annexed drawings, making a part of this specification, in which—

Figure 1 represents a front view of the stove when in use.

Figure 2, an interior view.

Figure 3, a top view, with the vase removed, and exhibiting the knob or trigger, pipe-hole, &c.

Figure 4, a view into interior from top, showing the upper shutter closed.

The nature of my invention consists in a stove which will be safe, and self-acting, and protecting in case of accident to railroad-trains.

In the drawings, fig. 1 represents the stove as in use, A being the ordinary opening for supplying the coal or wood, and B the door or shutter of same, which slides to one side. H is the ash-pit, kept closed by means of the screw K, excepting when otherwise required. In case of any violent accident to the train, and danger from the stove, the surmounting vase L, kept from falling an unnecessary distance by the chain M M, instantly falls from the recess R, fig. 3, in which it stands, displaces the knob or trigger N, and interior connecting

chain O, fig. 2, which movement simultaneously closes and fastens on either side, by the spring S and catch T, an inner shutter P, fig. 2, allows the door C to drop from the arm Q, fig. 2, which held it up, is held in this position by the spring E in the slot D, fig. 1, and by the same movement the lever F is moved and closes the draught-slide G. To reset the stove for use, the spring S is drawn back by a hooked rod introduced into arm-hole Q. The position of the stove may then change as it may, without danger from the fire, which thus becomes confined to a limited space, and securely enclosed. Fig. 4 shows the inner chain detached, and the spring, catches, arm, &c., of upper shutter.

Having thus described the construction and operation of the stove,

What I claim, and desire to secure by Letters Patent, is—

1. The knob or trigger N, in combination with the vase, for the purpose set forth.
2. The inner catch T, with the shutter P, its spring S, and arm Q, as herein described and shown.
3. The falling door or shutter C, and spring E, acting in combination with the slot D, the lever F, and slide G, arranged to operate substantially as herein described, and for the purposes set forth.

JOHN C. ECKERT.
